SUMMER BARN

Caleb G. Clarke, 1540 W. Market St.,
Akron, Ohio 44313

Filed Apr. 10, 1969, Ser. No. 16,664

Term of patent 14 years

Int. Cl. D25—04

U.S. Cl. D13—1

FIG. 2

FIG. 3

FIG. 4

FIG. 1 is a perspective view of the summer barn showing a horse and an attendant, as well as a stall closure and tree in phantom for illustrative purposes only;

FIG. 2 is an end elevation taken from one end, the opposite end being identical in appearance;

FIG. 3 is a side elevation, the opposite side being identical in appearance; and

FIG. 4 is a top plan.

I claim:

The ornamental design for a summer barn, as shown and described.
